UNITED STATES PATENT OFFICE

ARTHUR T. CHESTER AND A. CLAXTON CARY, OF RYE, NEW YORK

INTAGLIO PRINTING PRESS

Application filed August 13, 1929. Serial No. 385,504.

Our invention relates to printing presses adapted to print from intaglio steel plates and the objects of our invention are to overcome the many difficulties now encountered in this form of printing, to reduce the cost of production and increase the rate of production in a marked degree.

Printing presses for intaglio printing now generally used consist of a bed which supports the plate, and a roller which is applied with great pressure to the surface of the plate in order to produce an impression on the paper interposed between the plate and roller. To obtain as high production as possible it is customary to use a large plate and to carry thereon as many engravings of the subject to be printed as possible. A large plate, however, introduces difficulties which to a great degree nullify the production advantages obtained by its increased size. When the plate is hardened, as it usually is, some warping takes place and in order to print from such a plate the process of "make ready" is long and tedious. It is likewise necessary to apply a very heavy pressure to the printing roller or cylinder in order to obtain a satisfactory impression and frequently such pressure results in the bending of the cylinder shaft or the breakage of some other part of the press.

The paper to be printed upon usually requires some degree at least of wetting and this is not always easy to obtain to the proper degree and it is difficult to obtain uniformity of production because of the necessity of maintaining the proper degree of moisture under different conditions of atmosphere.

The difficulties above enumerated, and others, are completely overcome and added advantages obtained by our present invention, the very important feature of which is the substitution of fluid pressure applied directly to the paper covering the intaglio plate, for the present printing bed, and roller, the fluid pressure being applied through a flexible medium; together with automatic means for successively feeding plates to the printing head, ejecting the plates after printing, inking and wiping them automatically and returning them to the printing head.

Another important feature is the provision of means for printing by fluid pressure, from a plurality of intaglio plates simultaneously. Preferably such plates are arranged one above another in a printing head, but other arrangements may be used and we do not desire to limit ourselves to the construction shown.

Further features reside in various control devices which insure the proper relative timing of the printing operation and the plate feeding and ejecting operations.

A still further feature of the invention consists in automatic means for changing a plate, that is to say for substituting for a plate which is passing through the usual cycle of being printed, inked and wiped, a new plate, without stopping the regular cycle of operation of the press.

Other features and advantages will become apparent from the following detailed description and claims when taken in connection with the accompanying drawings, in which

Figure 1 is a top plan view showing rather diagrammatically the general arrangement of our improved printing press;

Figure 2 is a diagrammatic elevation on the same scale as Figure 1;

Figures 1-a, 1-b and 1-c taken together show in elevation and partly in section the printing head and the plate feeding, inking and wiping mechanism on one side of the head;

Figures 2-a and 2-b show part of the same mechanism in plan;

Figure 3 is a section through a plate holder and pressure container on a scale somewhat larger than that shown in Figure 1-a;

Figures 4, 5 and 6 represent in more or less diagrammatic form the parts concerned in the positioning of a plate in the printing head and the ejection therefrom of a plate from which a printing impression has been taken;

Figures 4-a, 5-a, 6-a, 6-b and 6-c show diagrammatically the various positions of a plate in passing from the lower track level to the higher track level;

Figure 7 is a view showing the plate-chang-

ing mechanism in a different position from that shown in Figure 1—c;

Figure 8 is a plan view of a portion of the plate changing mechanism;

5 Figure 9 is a side elevation thereof;

Figure 10 is a section showing the operation of the switch shown in the lower portion of Figure 9;

10 Figure 11 is a detail showing the means for operating this switch;

Figure 12 is a top plan view of some of the mechanism connected with the wiping and polishing of the plates, showing the feed rolls for the cloth and some of the mechanism for reciprocating the wipers and polishers;

Figure 13 is a view partly in elevation and partly in section showing the same mechanism;

20 Figure 14 is a detail of the bearing for the bed which supports the plates during the wiping and polishing operation;

Figure 15 is a detail of this mechanism viewed from the outside of the supporting frame;

Figures 16—A, B—C is a composite, partly sectional and partly diagrammatic view, illustrating the action of the valves controlling the admission of fluid pressure to the 30 piston and also showing in diagrammatic form the various circuits and the method of control;

Figure 17 is a side elevation of the composite switch shown in plan in Figure 1—b;

25 Figure 18 is a section showing the arrangements of the contacts of this switch;

Figure 19 is a detail of a drive from the chain to the ink fountain roller;

Figure 20 is a detail of the switch 158 shown in dotted lines in Figure 1—a and controlled by the piston;

Figure 21 is a detail of a plate-engaging driving lug; and

Figure 22 is a detail of the stops for the 45 pressure containers.

Since one of the important objects to be attained is a printing press capable of large production, we have shown in the preferred embodiment of the invention a printing head 50 arranged to accommodate a plurality of printing plates and to print from these simultaneously.

Since a further object of the invention is the attainment of continuous, automatic operation, we provide duplicate conveyor mechanisms whereby a number of plates are fed into the press, and the press operated to print from such plates simultaneously, the plates being then removed from the press to be prepared for another printing operation.

The general layout of the press is indicated diagrammatically in Figure 1 wherein the numeral 1 represents the printing head capable of accommodating a number of plates 35 at the same time and while in this particular

layout, four plates may be printed from at once, the invention is not necessarily limited to this number and, of course, a less number of plates may be used if desired.

The plates are fed to the head by means of conveyors in the form of endless chains running both ways from the head, there being a second set at right angles to the first set, the four sets of plate conveyors being exactly alike.

75 The printing head itself is shown in enlarged sectional view, Figure 1—a, and consists of a base 2 from which rise four pillars 3 surmounted by a pressure-sustaining head or cap 4, the pressure head being made of steel or other suitable material and capable of withstanding the necessary pressure. The base carries a piston 5 operated by fluid pressure and through which the printing is effected.

80 Printing pressure is applied to the plates through the medium of fluid pressure containers each having a flexible wall adjacent the printing surface of a plate. These fluid pressure containers are shown in Figure 1—a at 6, and in a somewhat enlarged view in Figure 3. Each consists of a plate recessed on its lower surface, and cemented in the recess is a bag of rubber or other suitable flexible material, the corners being reinforced by leather. The outside edges of each container have attached thereto lugs 8, Figure 2—a and Figure 22, which lugs project into grooves 9 in posts 10 which serve to guide the containers for limited vertical movement within the printing head. Inside the grooves 9 are stops 11 so placed that when the lugs 8 rest upon these stops the containers are 95 equally distant apart and out of contact with each other.

100 Normally the piston 5 is in its lower position shown in Figure 1—a, and the containers occupy the positions shown in this figure, with a plate holder containing a plate to be printed, resting upon each container except the top one. The bottom plate rests upon the top of the piston.

105 As shown in Figure 3 each plate holder 12 supports a plate 13 which is retained in position by a frame 14 surrounding the plate and having undercut portions as shown, the frame being secured to the plate by screws 15.

110 Figure 3 also shows a pressure container 6 with its flexible face consisting of a bag 16 having the reinforcement 17 already referred to.

115 Fluid pressure is applied directly to the paper covering the plate through the medium of the flexible face of the pressure container, the fluid being introduced into the container through a connection 18 tapped into one side of the container as shown at 19.

120 The pressure sustaining head or cap 4 of the printing head and the pillars 3 are designed to withstand the total pressure of the 130

piston when full pressure is applied to its base. The piston size is such that the area of its face to which the fluid pressure is applied is greater than the area of the lower face 5 of the flexible wall of the pressure container.

On opposite sides of the printing head and on a level with the top of the piston when it is in its lowest position as shown in Figure 1—*a*, are pairs of tracks 20 leading horizontally away from the head. Above and parallel to these tracks is a second and shorter pair of tracks 21 at the level of the upper face of the lower container. The same relative arrangement tracks are placed on the two sides 15 of the press at right angles to those just described, as shown in Figure 1, these tracks being at the level of the upper face of the second and third containers respectively when these containers are in their normal 20 position shown in Figure 1—*a*, with the piston down. These support and guide a plate holder with its plate and along which it is conveyed on rollers described later.

The operation in general consists in pushing 25 a plate into the printing head from opposite sides thereof at two different levels. This operation will be apparent from Figure 1—*a* where a plate holder is shown at the right, just outside of the head at a lower level, and 30 a plate holder at the left side at a higher level. There is also a plate in the head, one adjacent each of the plates positioned outside. If the outside plates are each moved towards the head they will push out of the head the plate 35 which is already in the head and themselves occupy the place of the ejected plate. Each plate is conveyed to the ends of the tracks when the direction of travel of the conveyor is then reversed and the plate is brought back. 40 During this travel it passes under an inking roller and under wiping and polishing members and again returns to the position shown in Figure 1—*a*.

In the construction shown, there are four 45 plates in the press at the same time and four plates are outside of the head being prepared for printing, the operation being a continuous one. That is to say, the piston is raised and pressure applied through the pressure 50 containers, to the plates within the head and during this time the plates outside of the head, after being conveyed to the inking, wiping and polishing mechanisms, are brought back to the printing head which in the meantime has been operated to perform the printing, the piston having again descended to the 55 lower position shown in Figure 1—*a* so that the head is open ready to receive the inked and wiped plates and to have the plates which 60 have just been printed, ejected therefrom.

Since the means for conveying the plates to the inking, wiping and polishing mechanism is identical on each side of the printing head it will be necessary to describe only one 65 of these mechanisms in detail.

As shown in Figures 1—*a* and 1—*b*, (which should be read together), the tracks 20 extend from a point adjacent the printing head to a point indicated at 24, Figure 1—*b*, at which point the track is interrupted by a 70 hinged connection 25 for a purpose which will be explained later. The upper tracks 21 are relatively short, their purpose being to receive a plate ejected from the head and transfer it to the lower track 20 along which 75 it is conveyed to the mechanisms which prepare it for the next printing operation. The upper tracks 21 therefore have a hinged section 26, Figure 1—*a*, and a hinged section 27, Figure 1—*b*, situated at a definite distance 80 apart, this distance being substantially equal to that between two sets of rollers 29 carried near the front and at the rear of a plate holder. These track sections are also shown in Figures 5 and 6, 4—*a*, 5—*a*, 6—*a*—*b* and *c*. 85 The tracks 21 just to the left of the hinged section 26 are cut away sufficiently to permit the rear rollers 29 to pass from the tracks 21 down the incline 26 to the lower tracks 20, Figure 6, the front rollers at the same time 90 passing down the incline 27 so that a plate holder passes by a parallel movement from the upper tracks 21 to the lower tracks 20.

Movement of the plate holders and plates along the tracks is effected by conveyor chains 95 22 driven by sprocket wheels, said chains travelling parallel to the tracks and outside thereof.

Adjacent to the printing head on four sides 100 thereof these conveyor chains pass about sprocket wheels 23, shown adjacent to the pillars 3, Figs. 1—*a* and 2—*a*, one of which is shown to the right of the printing head, Figure 1—*a*. These wheels turn on stub shafts 23—*a* projecting from the pillars 3 as 105 shown in Figure 2—*a*.

The upper portion of each chain beyond the short tracks 21 is deflected from a straight line by two additional sprocket wheels 31 and 32, Figure 1—*b*, to conform to the track 110 at the incline 27. At the ends remote from the printing head each sprocket chain passes over a sprocket wheel 33, Figure 1—*c*, the axis of this wheel having mounted thereon a spur wheel 36 engaging a pinion 37 driven 115 from a motor 60 supported on a suitable base 260.

Sprocket wheels 31 and 32 turn on stub shafts 31—*a* and 32—*a* passing into plates 38 secured to brackets 38—*a* screwed to the 120 pillars 3 (Figure 2—*a*).

For the purpose of conveying the plate holders towards and away from the printing head the sprocket chains carry lugs 34 and 35. These lugs are in transverse alignment but 125 the lugs 34 are in a different vertical plane from that occupied by the lugs 35 as is made clear from Figure 2—*a*.

One of these lugs 34 is shown in enlarged view in Figure 21. In this figure the lug is 130

shown as pivoted to a projection on one of the chain links, a spring normally tending to hold said lug against a stop 39. A lug so mounted will drive in one direction of movement of the chain while in the other direction of movement the spring will permit the lug to move past any obstruction in its path.

Each plate holder is provided on one edge with a plate 40 secured by screws. This 10 plate has its ends bent as shown in Figure 2-a, providing a vertical elongation at each end, constituting a lug 42 and by which lugs a plate holder is moved by the chains through the medium of the chain lugs 34 and 35 (Figures 4 and 5).

These figures show diagrammatically how a plate is delivered to and positioned in the printing head, and a plate from which a printing impression has been taken, ejected 20 from the head.

In Figure 4 a plate holder 12 at the right is being pushed out of the head by another plate holder 12 which is shown as positioned about half-way within the head, it being 25 driven in this direction by the lugs 35 of the chain engaging behind the plate holder lugs 42.

The sprocket chains on opposite sides of the printing head are driven in opposite 30 directions by the electric motors 60, there being one motor 60 for each pair of chains. Therefore, as the chain on the left side of the head operates to push its plate holder 12 into the head by the lugs 35, and eject the plate to 35 the right which has just been printed, the chain at the right of the printing head is pushing another plate holder 12 into the printing head which acts to eject a plate holder 12 whose plate has just been printed.

40 Figure 5 shows the completion of the positioning of two plates in the head and the complete ejection of two other plates from the head, the lower plate 12 having been completely ejected from the head on the left side and on to the track 20, while the plate 12 on the right side occupies the upper track 21. Figure 5 shows the position of the parts after 45 the lugs 35 have passed around the sprocket wheel 23 and have reached a position just in contact with the back of the lugs 42 of the lower plate.

As lugs 35 pass over sprocket 23 they act with camming effect on the lugs 42 of the plate holder to accurately position it in the 55 printing head. The plate 40 is of such width that its lower edge extends a little below the plate holder thereby forming a stop which abuts the piston in the case of the lowest holder; the plates 40 of the upper 60 holders abutting the pressure containers 6 as shown in Figure 1-a, whereby the plate holders are accurately positioned in the head in vertical alignment.

When the sprocket chains are moving 65 clockwise, 35 are the driving lugs as shown

in Figures 2-a, 4 and 5. When the motors 60 are reversed then lugs 34 become the driving lugs and 35 the advancing lugs. Since these lugs overhang the plate holders, as shown in Figure 2-a, the advancing lugs 34 must pass from above to below a plate holder as such holder is entering the head. To permit this each holder is notched as shown at 70 34a, Figure 2-a.

Since the operation of all of the chains is alike we shall trace the movement of a plate 12 which has just been ejected from the head and rests with its rollers 29 on the track 20 to the left of the head. A plate holder 12 is always returned to the head at 75 the same level it previously occupied. Therefore this particular plate whose progress we shall trace will be returned to the same position it is shown to occupy in Figure 5. We shall later describe how a plate holder ejected 80 on to the tracks 21 is returned to the same position.

Starting then with a plate in the position shown in Figure 5, continued operation of the driving chains will cause the lug 35 to carry this plate holder 12 along with them, the lugs 34 at this time being the leading lugs and performing no function until the direction of drive of the chain is reversed, as will 85 be later described.

It may be here stated parenthetically that as a plate holder is ejected from the printing head it operates a switch 193 to close a circuit through the motor 60 appropriated to 90 its driving chains. This switch is a composite one and also controls the supplying of fluid pressure to the piston 5 whereby the plates are brought in contact with the containers. A description of its construction and detailed mode of operation will therefore 95 be deferred until later.

Since the plate holder whose travel we are tracing has been ejected from the head directly onto the tracks 20, the rollers 29 will 100 pass under the hinged sections 26 and 27 of the tracks 20 and lift them. These sections are connected and constructed to bear with sufficient friction against their pivots so that they remain in whatever position they are left and such position is shown in Figure 6, ready to permit the rollers 29 to pass under these sections when this plate holder 105 is returned.

As the plate holder 12 passes along the 110 tracks 20 it passes under the polishing, wiping and inking mechanisms shown in Figure 1-b, but due to the fact that it is received upon a movable bed or frame which at this time is in its lowered position, there is no contact between the elements of the polishing, wiping and inking mechanism and the face of the plate. The plate passes on to the extreme left portion of the track 20, shown in Figure 5.

115 As the plate approaches the end of track 120

20 shown in Figure 1—c, its lug 42 encounters an arm 44 of a reversing switch shown in Figures 8, 9, 10 and 11. The arm 44 of this switch is shown at the extreme left of Figure 5. Figure 11, however, shows the arm 44 in its normal position with the lug 42 just about to make contact with it and move it to the dotted line position, the lug 42 being shown just leaving the arm at this point. The arm 10 44 is pivoted to a second arm 45 at 46, there being a lug 47 projecting from the arm 45 to form a rigid connection between 44 and 45 when the arm 44 is encountered by a plate approaching from the right in Figure 11. 15 Arm 45 is secured to a vertical shaft 48, Figures 9 and 11, which shaft carries a lower arm 49 to which is pivoted a pawl 50 for engagement with a ratchet 51, in driving relation with the electrical contact elements 53 20 of the reversing switch. A spring 52 surrounds the shaft 48 and holds it in such position that the arm 45 and contact arm 44 normally occupy the full line position shown in Figure 11. Therefore, when the plate 25 holder passes beyond the dotted line position of the lug 42 the spring 52 snaps the shaft and parts connected therewith back to normal. When a plate holder is moving in the opposite direction and it encounters the arm 30 44, said arm moves on its pivot 46 out of the way and permits the plate holder to pass on without affecting the switch. The switch elements, therefore, are moved only in one direction through the ratchet 51 and pawl 35 50. When the switch elements are in the position shown in Figure 10 and with either one of the contact members 195 or 244 closing the circuit to the motors 60, the current passes from the battery 55 through either 40 contact member 195 or contact 244 and lead 56, to contact 57 of the switch element 53; thence by way of contact arms 58 to lead 59 and through the motor 60. From the other side of the motor it passes by way of lead 61 45 to contact arm 62; then by way of contact 63 to lead 64 back to the battery.

Upon the actuation of the arm 44 by the passage of each plate the switch members are turned through 90°. When, therefore, the 50 switch elements are so turned as to occupy the dotted line position shown in Figure 10, the current then passes from the battery 55 through contact members 195 or 244 and lead 56 to contact 57, but at this time the arm 58 55 is in engagement with contact 65 so that the current then passes through lead 66 to the motor on the opposite side thereof, passing thence through lead 67 to contact 68 which is then in electrical connection with arm 62 which conveys the current to contact 63 and through lead 64 back to the battery.

The motor being reversed the plate now moves in the opposite direction under action 60 of the lugs 34 which now become the driving lugs, and when the plate reaches the position

shown in Figure 6 it operates mechanism which controls the inking of the plate and its subsequent wiping and polishing. The details of this mechanism will now be described.

In order that the plate may be properly inked and subsequently wiped and polished, such a plate upon reaching the position shown in Fig. 6 passes upon a movable bed. This bed 70, Fig. 1—b, is supported upon a suitable base 71 having frame members 72 extending upwardly a sufficient distance to support various mechanisms of the press.

The bed 70 is in the form of a casting having side members 74 and 75 and a central rib 76. The side members 74 and 75 and the upper portion of the rib member 76 are notched to support a series of rollers 77 shown in Figs. 1—b and 2—b.

The bed 70 is supported for limited vertical movement on the base by two shafts 78, the ends of which are eccentrically supported in circular bearings 80 shown in dotted lines in Fig. 13 and in detail in Figs. 14 and 15. The bearings 80 are inserted from the outside 90 of the support 71, said supports on either side being cut out to the size of the bearing and being bored through with a tool of smaller diameter so as to leave an edge to prevent the bearing from moving inwardly, this edge being cut away for a portion of its circumference to permit the eccentric shaft to have the proper clearance. To further secure the shaft against movement, a retaining member 82, shown at Fig. 15, is screwed to the support 71. 100

To the inside faces of the bearings 80 are secured arms 84, Figs. 1—b, 13, 14 and 15. These arms are connected by a link 85 pivoted at its left hand end to an arm 86 secured to a shaft 87 which extends transversely of the machine and is pivoted in the frame members 72, as shown in Fig. 2—b. There is one arm 86 on either side of the machine and likewise arms 84 and links 85. From the construction just described it will be apparent that if the links 85 are moved so that the arms 84 rotate from the full line position shown in Fig. 1—b to the dotted line position shown therein, the whole bed 70 and its supporting rollers 77 will be elevated. The portion 25 of the track 20 being hinged at 24 will permit this movement, the ends of the movable portion 25 being joined to the bed by slotted connections 88.

When the bed is in its raised position the center of each shaft 78 is in a position slightly beyond the center of the bearings 80 so that the bed must rise slightly in order to assume its lowered position.

A spring 90, Figs. 1—b and 2—b, connected to the shaft 87 at one end and to the base 71 at the other, causes this slight upward movement of the bed to enable the shaft 78 to pass the dead center when gravity, aided by said 130

spring, will cause the bed to be lowered when a plate holder has passed clear thereof.

Means are provided to cause the bed to be automatically raised when a plate is being driven on to the bed by the chains. For this purpose there is secured to the middle of the shaft 87 a collar 91 having an extension 92 shown in Fig. 1—b, forming a lip. Adjacent to the collar 91 is a loose arm 93 carrying an extension 94 forming a lip which is adapted to engage the lip 92. These lips are kept in contact by a spring 137 coiled about the shaft 87 and pressing against the back of the arm 93. The arm 93 is shown in normal position in Fig. 5 and when a plate holder approaches it from the left it moves such arm to the position shown in Fig. 6 thereby raising the bed 70 just as the plate is about to pass thereon.

The purpose of raising the bed at this time is to bring the plate into contact with an inking roller and with the wiping and polishing mechanisms.

The inking system consists of a fountain 100 open at the bottom and exposed to a roller 101.

It is desirable that this roller be constantly rotated to prevent the ink from drying or accumulating on its lower portion. Mechanism for accomplishing such rotation is constructed and operates as follows:

Two small sprocket wheels 102 and 103 permanently engage above and below one of the chains 22 as shown in Fig. 19. These sprocket wheels are also shown in Fig. 13. The shafts of these sprocket wheels carry on their ends smaller sprocket wheels 104 and 105 respectively. The axis 107 of the roller 101 carries two sprocket wheels 108 and 109 loosely mounted thereon. On the opposite side of each of these sprocket wheels is secured a ratchet wheel 110, secured to the axis 107, each engaged by a pawl 111 secured to the face of the sprocket wheel, which pawls engage their respective ratchet wheels in the same direction. A sprocket chain connects the sprocket wheels 104 and 109 and another sprocket chain connects the wheels 105 and 108. By this construction the roller 101 is always rotated in the same direction no matter which way the chains 22 happen to be travelling.

The ink which is taken up by the roller 101 is transferred to the plate through the medium of a roller 112 and a roller 113. The roller 112, however, is normally free from contact with the rollers 101 and 113 and assumes this position when the bed 70 is in its lowered position. When the bed is raised, however, means are provided whereby the roller 112 drops down and transmits motion from the roller 101 to the roller 113 which then applies ink to the plate.

The bed 70 effects this control of the roller 112 by means of two arms 114 and 115 extend-

ing in opposite directions from the bed and passing through slots in the side of the base 71. Extending upwardly from each arm 114 and 115 on either side of the base is a link 116, the other ends of these links being connected respectively to two levers 117 pivoted intermediate their ends to stub shafts extending from the supports 72, as shown in Fig. 13. In this figure only the left hand link 116 and lever 117 is shown because this mechanism is hidden, on the other side of the machine, by the frame supporting the rollers which carry the cloth for the wipers and polishers. The ends of the levers 117 opposite to those to which the links 116 are connected are provided with elongated slots shown in dotted lines in Fig. 1b into which the axle 118 of the roller 112 is supported. Therefore, when the links 116 move upwardly with the bed, the levers 117 rock about their pivots and permit the roller 112 to be lowered and establish a connection between the roller 101 and the roller 113 and the ink taken up by the roller 101 is transmitted to roller 113 and hence to the plate.

The wiping and polishing mechanism

After the plate has been inked it immediately passes to the wiping mechanism and then to the polishing mechanism. These mechanisms are supported by the same frame members 72 already referred to. It is desirable to reciprocate the parts which come into actual contact with the plate and for this purpose two bars 120 and 121 are provided. These bars pass through openings in the members 72 which openings provide for reciprocatory movement of the bars across the bed 70. Between the members 72 these bars bear against a bridge 122, Fig. 13 and Fig. 1—b, screwed between the inside faces of the members 72.

Each bar carries at its center a bracket 123 having an elongated slot 126 therein, the bracket for the bar 120 being shown in Fig. 13. U-shaped wipers 124 fit over the bars 120 and 121 and through them from side to side pass short shafts 125, Figs. 1—b and 13, these shafts also extending through the slots in the brackets 123. There is a bar 120 and a bar 121 for the wipers shown in Fig. 1—b and another set of bars 120 and 121 for the polishers 124a situated just to the right of the wipers. They both operate in substantially the same way and are driven by the same mechanism.

Reciprocatory motion of the bars 120 and 121 is transmitted to the wipers 124 through the medium of the brackets 123 and shafts 125.

In order to permit adjustment of the pressure of the wipers against the plate the brackets 123 have their slots 126 slightly elongated.

Springs 127 fit over lugs 128 on the wipers and rest against wedge-shaped wear plates 129.

130 which have circular openings therein and are adapted to move up and down on the pins 132 carried by the reciprocatory bars 120 and 121. The tension of the springs 127 and 128 5 may be varied by wedge-shaped members 133 having slots therein through which the pins 132 pass, the under face of each wedge bearing against a wear plate 130. Longitudinal adjustment of the wedges is provided in the 10 form of screw-threaded rods 135 and 136, one for each member 133, these rods being attached to the wedges so as to permit rotary motion of the rods, the opposite end of each rod being squared to receive a suitable tool 15 for turning the rod. It will be readily noted that movement of these rods will cause greater or less tension to be applied to the wipers by the springs 127.

In order to limit the downward movement 20 of the wipers under action of these springs, limiting stop members 138, Fig. 13, are screwed to the inside upper face of a wiper. These are engaged by lugs 139 depending 25 from the bars 120 and 121, the length of the lugs being such that they prevent the shafts 125 from touching the bottom of the slots 126.

It is desirable that the bars 120 and 121 30 be reciprocated only when a plate is about to pass under the wipers. Therefore, means are provided whereby when the bed 70 is raised as just described current will be turned on to a motor which operates to reciprocate these bars. For this purpose an ordinary 35 electric switch 140 is provided, Fig. 1b, which has an arm 142 having a forked end which engages the arm 115 which, it will be remembered, projects from the right side of the bed 70 as shown in Fig. 13. The arm 142 and 40 switch 140 are also shown in dotted lines, Fig. 1b. The switch is so constructed that when the bed is in its upper position current is turned on to an electric motor 143, Figs. 12 and 13. One end of the motor shaft carries a beveled pinion 144 which meshes with a horizontal beveled gear wheel 145 turning 45 about the shaft 146 supported by a bracket 147, Fig. 13. The upper face of the gear 145 carries an eccentric 148, Fig. 12, whose 50 rod 149 is provided with a head 150 movable in a slot 151 in a three-armed member 152 pivoted at 153 and supported by a suitable bracket projecting from the member 72. The other two arms of the three-armed member 55 152, as shown in Fig. 12, are provided with elongated slots with which engage pins carried by the bars 120 and 121 respectively. When the motor is in operation, therefore, 60 the eccentric will cause the three-armed member to be rocked and the bars 120 and 121 to be reciprocated in opposite directions, thus moving the wipers in opposite directions across the face of the plate.

The polishing mechanism is constructed 65 exactly like the wiping mechanism which has

just been described, the polishers 124a being reciprocated in the same way by a three-armed member similar to the three-armed member 152, there being a rod 154 attached to the head 150 underneath the three-armed member 152 so that the same eccentric driven from the motor operates both the wipers and polishers. By adjusting the head 150 in the slot 151, variation in the amount of reciprocation of the wipers and polishers may, of course, be effected. 70 75

Cloth feeding mechanism

The cloth for the wiper is carried on a supply roll 156, Figs. 12 and 13, and passes under a directing roller 157, then half round the deflecting roller 158 (see also Figs. 1-b 80 and 12) which is placed at an angle of 45° with the bed and therefore causes the cloth to take the direction of the bed. The cloth then passes over roller 159 (Fig. 1-b) and then around under the wipers 124 and up over the rollers 160 and 161 and about the deflecting roller 162 and between the feed rollers 163 and 164, thence to the take-up roller 165. 85 90

The cloth for the polisher is supplied from roller 166 and passes over the directing roller 167 around a deflecting roller 168 and over the roller 169, then around the polishers 124a and over the roller 170, then around the deflecting roller 171. It then also passes between the feed rollers 163 and 164, and is taken up by the roller 172. 95

The several rollers just described are supported in suitable brackets extending from the frame members 72 or are supported directly by these members. 100

The directing rollers 157 and 167 are provided to properly direct the cloth from the supply rolls 156 and 166 to the deflecting 105 rollers 158 and 168 respectively as the supply rolls diminish in size.

The feeding of the cloth is brought about by movement of the bed 70 from its lower to its upper position, since it is desirable to have 110 a fresh portion of cloth positioned under the wipers and also a fresh portion positioned under the polishers when the plate is approaching the position when it is to be wiped and polished. Therefore, the same arm 115 which has already been described as performing the function of connecting the motor for reciprocating the wipers, is also availed of to feed the cloth. Connected to the arm 115, 115 therefore, is a rod 174, the connection being somewhat loose to permit of slight lateral motion as the rod does not move in the same plane as the arm. The other end of the rod is connected to one end of a bellcrank lever 175 pivoted at 176 to a bracket 177, Fig. 13. One arm of the bellcrank lever 175 is slotted, 120 Fig. 12, and adjustably secured in this slot is one end of a rod 178 which leads up to and is connected with the end of an arm 179 loose on the extension of a collar which turns 125 130

about the end of the axis of the feed roller 163. Secured to this axis is a ratchet wheel 180 with which a pawl 181 on the arm 179 engages.

5 It will therefore be seen that each time the bed 70 is raised, the feed roller 163 will turn through an angle which of course will vary with the point at which the rod 178 is secured in the slotted arm of the bellcrank 10 lever 175. It will be noted that the feed roller 163 is considerably larger than the feed roller 164. This is made necessary by reason of the fact that it is not mechanically feasible to give to the pawl 181 more than 15 120° of angular movement and since it is frequently desirable to give to the cloth a linear movement of as much as four inches, the large feed roller has been used.

Operation of the take-up rolls is performed by the same motor 143 which reciprocates the wipers and polishers, and for this purpose the shaft of the motor has secured to it a pulley 182, Fig. 12. This drives a belt which passes over another pulley 184 20 on a shaft 185. This shaft also carries two other pulleys 186 and 187 shown in dotted lines, Fig. 13. The pulley 186 is connected to a pulley 188 secured to the axis which turns the take-up roller 165, by a cross-slip 25 belt.

The pulley 187 is connected to a pulley 189 secured to the axis which turns the take-up roller 172 by a slip belt which, however, is not crossed. By this means the take-up feed 30 rollers are turned in the proper direction and the slip belts provide for the different amounts which these rollers need to be turned in order to take up the slack as the rollers increase in size.

40 Since this invention contemplates the duplication of the various mechanisms for handling the plates by adding an additional tier or tiers of these mechanisms and increasing the height of the printing head to correspond, 45 the described arrangement of the take-up and feed rollers at the side is of particular advantage. If such rollers were placed above the wiping and polishing mechanisms, the height of the press would go beyond all 50 convenient limits with added tiers of plates and the mechanism necessary for the handling of the same.

Although a plate holder as it passes onto the bed 70 clears the arm 93, the bed does not 55 at once return to normal position by the pull of the spring 90 due to the fact that the plate is at that time under the inking roller or under the wipers and polishers and this prevents the bed from lifting the slight amount, 60 which it must do as previously described, owing to the fact that the centers of the eccentric shafts 78 are at this time still slightly beyond the centers of the bearings 80. Just as soon 65 however as the plate passes the last polishers

124a, the spring 90 returns the bed to its lower position.

It will be remembered that the plate whose progress is being described was a plate which was ejected from the printing head at a lower 70 level and in passing under the hinged sections 26 and 27 of the upper tracks 21, the rollers 29 of this plate raised both these sections, which due to the friction of their bearings, remained in set position as shown in 75 Fig. 6. Therefore as this plate approaches the head, its rollers will pass under the ends of the raised sections and the plate will be delivered to the position shown in Fig. 5 except that with the reversal of the driving 80 chains, the lugs 34 are at this time in engagement with the lugs 42 of the plate and are acting as driving lugs. At this position the switch 193 will be opened to break the motor circuit at 195, Fig. 10.

85 It will also be remembered that a plate is always returned to the same level of the printing head from which it was previously ejected. The plate whose excursion has just been traced was ejected from the lowest 90 level and has been returned to the same position from whence it started.

Before describing the operation and control of the printing head, it will be logical to explain the difference in the action of 95 the conveyor mechanism when a plate holder is ejected from the printing head at the next higher level, that is to say, when a plate-holder is ejected onto the track 21 instead of onto the track 20. This operation will be 100 understood by considering Figs. 4-a, 5-a, 6-a, 6-b and 6-c. In Fig. 4-a, a plate is shown as being pushed out of the head onto the track 21 at the left. Fig. 5-a shows such plate-holder completely outside of the 105 head and in the full line position; the advancing rollers 29 are just about to engage the incline of the section 27. The following rollers 29 are just about to enter the gap in the track 21 in front of the pivot of the hinged section 26. The front rollers did not pass into the gap because at this time the center of gravity of the plate and holder is within 110 the head. In the dotted line position of the plate-holder shown in Fig. 5-a it has moved down to the track 20 and the weight of the plate-holder has forced down the sections 26 and 27 which were left up when the lower plate-holder passed into the head. Fig. 115 6-a shows the plate as having advanced a little farther. Owing to the fact that the advancing rollers 29 move down on the outside of the section 27, said section remains in its lower position until the following rollers 29 pass under it when it is raised thereby and then occupies the position shown in Fig. 6-b. The plate passes on to the end of the tracks 20 where it operates, as previously described, to reverse the motor which drives the chains. The plate then begins 120 125 130

to approach the printing head and passes under the inking, wiping and polishing mechanisms and is returned, and Fig. 6—b shows it as nearing the printing head. This plate must be delivered to tracks 21 and therefore means must be provided to lower the section 27, but such lowering must not occur until after the advancing rollers 29 have passed under it. When the plate has reached nearly the position shown in Fig. 6—a, a lug 190 projecting down from one of the chain links on each side, encounters a projection 173 extending laterally from the section 27 just before the trailing rollers 29 are about to reach said section, said lugs 190 camming the section down to the position shown in Fig. 6—c so that the trailing rollers engage the section 27. At the same time, the advancing rollers 29 engage the section 26 and the plate-holder is moved by a parallel motion from the lower tracks 20 to the upper tracks 21.

Mechanism for controlling the printing

From the foregoing it will be understood how the plates are ejected from the printing head, conveyed to the inking, wiping and polishing mechanisms and returned to the head. It is, of course, to be understood that the paper is applied to the plate after it leaves the polishers and before it is ready to be reinserted into the head. After the printing has taken place the paper is removed before the plate passes under the inker. Referring now to Fig. 1—a, it is assumed that four plates which have been inked and wiped and each having paper placed thereon, are in the printing head. It now becomes necessary to operate the piston to effect printing. The mechanism for controlling the supply of the fluid pressure is under the control of a plate holder which has just been ejected from the printing head.

This control is effected by means of the switch indicated in its entirety by the reference character 193 and to which reference has been already briefly made. This switch is shown in plan in Fig. 1—b and in detail in Figs. 17 and 18. As a plate holder is ejected from the printing head one of its lugs 42 encounters an arm 192 constituting an operating part of this switch. The arm 192 is secured to a vertical shaft 155 which extends below the lower run of the chain 22 and is there provided with an arm 141. The switch comprises a movable part carrying contact members 195 and 196 and a stationary part carrying terminals 197, 198 and 199, 200. The contact member 195 has been referred to in discussing the reversing switches for the motors 60, shown in Fig. 10, and is one of the switches which controls the closing of the circuit through a motor 60. When a plate is ejected from the printing head as indicated in Fig. 1—b, one of its lugs 42 encoun-

ters the arm 192 and moves it to the dotted line position shown in Fig. 17. This causes the contact member 195 to bridge the terminals 198 and 200 and to thereby close the circuit through the motor 60 controlled by this plate.

Since it is desirable to open the motor circuit as the plate approaches the printing head in the opposite direction, the arm 192 must be so connected to the switch that it is likewise in the path of a lug 42 when the plate is approaching from the opposite direction. In Fig. 17 the lug 42 is shown in dotted lines as just about to leave the end of the switch arm 192. The arm 141 is, therefore, not directly connected to the movable part 194 but is connected thereto through the springs 202 so that as the lug 42 leaves the arm 192 it immediately is returned to central position under action of one of the springs 202 acting through the arm 141 and shaft 155. Arm 192 then lies in the path of a lug 42 ready to be moved thereby as the plate holder returns towards the position shown in Fig. 1—b. The position of that shown in dotted lines, Fig. 17.

The control of the application of the pressure to the piston is brought about when the member 196 bridges the terminals 199 and 200. It is of course to be understood that one of these switches 193 is provided for each set of plates because there must be no starting of the piston until all of the plates are clear of the printing head. The contacts 196 therefore are arranged in series so that they must be closed at all of the switches before the hydraulic pressure is applied. The circuit from these switches and the connections to the motor for controlling the admission of pressure to the piston can be best understood by reference to Figs. 16 A, B and C. This view is a composite sectional and diagrammatic view. Portion A of this view is taken along line 16A—16A, Fig. 2—a; portion B is taken along line 16B—16B, and portion C is taken along line 16C—16C.

The motor is indicated a 201 and on the shaft thereof is a small pinion 203 in gear with a wheel 204 secured to a shaft 205 carrying a stout wire contact 206 which normally engages conducting segment 207 extending about one-third around the interior of an insulating ring 208. Also secured to the shaft 205 is a cylindrical valve 183 having a port 209 which normally registers with an exhaust chamber 191.

In order to conserve the high pressure necessary to produce satisfactory printing from intaglio plates, we provide in the present arrangement, means for first admitting relatively low pressure to the piston and to the pressure containers so that the piston moves up and takes up the lost motion between the various containers and the plates and all of the containers are filled before the high pres-

sure necessary for printing, is applied. The motor 201, therefore, is so controlled that it operates in two stages, first to admit low pressure fluid and then high pressure fluid.

5 Starting, therefore, with the parts positioned as shown in Fig. 16—C and with all of the contacts 196 closed, the circuit may be traced as follows:—From the motor terminal 210 the current flows through lead 211 to the 10 battery 212, wire 213, to terminal 199, thence through the contact member 196, Fig. 18, to the terminal 200, Figs. 18 and 16—C. From the terminal 200 it flows along wire 214 and thence through the contact member 196 of 15 each of the other switches 193 through connecting wires 216, 217 and 218 to the lead 219, to segment 207 of the motor switch; thence through the contact 206 to the valve shaft 205 and contact 220 and lead 221 to the 20 other motor terminal 222.

The motor 201 now starts and turns the valve 183 which closes port 191 from exhaust, the circuit just traced being maintained so long as the contact spring 206 remains in contact with the conducting segment 207. As 25 soon, however, as the contact spring 206 leaves the segment 207 and passes on to the conducting segment 224 the circuit just described is broken and the motor stops with the port 209 30 in alignment with the low pressure conduit 225. Low pressure fluid is then admitted below the piston, it flowing from the conduit 225 through the cylindrical valve 183 from which a conduit 226 leads underneath the 35 piston. There is also a branch conduit 227 connecting with 226 by which the fluid pressure is admitted to the pressure containers through a valve 228 leading to a chamber 223 with which all the containers are connected, 40 which valve is opened as the piston attains its highest position. This valve is normally spring-pressed to its seat as shown in portion A of Fig. 16 and is opened against its spring by means of a plate 229 secured to one side 45 of the piston and shown in section in Fig. 16—A and in dotted lines in Fig. 1—a. At the same time the plate 229 operates another valve 230 and closes a passage which provides an exhaust 242 for the containers.

50 The operation so far described has resulted in bringing the pressure containers close together with the paper on each plate in contact with the underside of the flexible wall of such container and all of the containers are 55 filled with fluid at low pressure.

The high pressure is now applied and the mechanism for controlling this operates as follows: As the low pressure fluid passes up the conduit 227 and through the valve 228 it 60 operates to lift a flap valve 231 to permit the fluid to enter a chamber 232 and operate upon a piston 233, the rod 234 of which is acted on by a spring 235 and normally tends to hold the piston down. The upper end of the pis- 65 ton rod operates against a contact member

236 and causes it to engage a second contact member 237 to thereby close a circuit through the motor 201. The spring 235 is of such tension that it does not permit the contact to be made until the whole system has attained full low pressure.

The circuit closer at 237 leads through wire 238 to the battery 212; thence along wire 211 to the motor terminal 210, through the motor to the terminal 222, wire 221, contact 220 and motor shaft to the wire contact 206, which it will be recalled is now in engagement with the conducting segment 224. This conducting segment is connected by a wire 239 which leads to the contact 236. The motor 201 then starts and continues running until the contact spring 206 has passed along the entire portion of the conducting segment 224 and has again reached the position shown in Fig. 16—c, at which time the circuit is again broken.

During this movement of the motor the cylindrical valve has been rotated so that its port 209 has moved to close conduit 225 and to cause said port to move past the conduit 240 leading from the high pressure fluid supply and during the 80 passage of the port 209 across the conduit opening 240 high pressure is applied to the piston and to the containers to cause printing from the plates. This pressure is sufficiently 85 high to produce satisfactory printing from the plates under the conditions which vary with thickness of paper, quality of ink, degree of wetness of the paper and other factors.

The gearing between the motor and the cylindrical valve is such that sufficient 90 time is permitted for the printing under the high pressure fluid during the time the port 209 is passing the port 240, so that when the contact is broken the port 209 is open to exhaust and immediately the piston begins to descend. As it does so the valve 230 is opened 95 to permit the pressure containers to exhaust. This may be brought about by connecting a pump or siphon to the chamber 242 since the valve 228 is closed as soon as the piston begins 100 to descend. The valve 231 immediately closes also so that the only escape for the water from the chamber 232 is through a small opening 241 controlled by a needle valve 129. The 105 purpose of this is to prevent breaking of the circuit at the contacts 236 and 237 before the valve 183 has been turned sufficiently to fully open the port 209 to exhaust. Otherwise there might be the possibility that the contact 206 would not reach the conducting segment 207 110 which it must do in order to have the operation of printing repeated. With the slow passage of water from the chamber 232 insured, the circuit through the motor is kept closed until it is broken by the contact 206 115 leaving the conducting segment 224.

It is preferred that the operation of preparing the plates for printing be so timed that the printing will have been completed and the piston 5 be in its lower position before 120

a set of newly prepared plates are ready to go into the head and the plates which have just been printed, ejected from the head.

Therefore, it is desirable that the motors 60 driving the conveyor chains be not stopped if the printing head is open and ready. To accomplish this the plate 229 attached to the piston closes a circuit through all of the motors 60 when the piston is down. The switch 10 for this purpose is shown in Fig. 20, a contact arm 244 being moved into engagement with a contact member 245 by engagement of the plate 229 with an insulating piece 246. When the contact 244 is closed, current passes 15 from the battery 55 to all of the motors 60 through the reversing switch elements 53 connected in parallel.

It will now be clear why in describing the action of the switch elements 53 to reverse the 20 motors 60, it was assumed that the contacts at either 195 or 244 were closed. The control of the contacts 195 by the plate holders is in the nature of a safety device. If the printing head is not positioned to receive a plate by 25 reason of the fact that the piston has not been sufficiently lowered, it is very important to stop the progress of a plate holder before it attempts to enter the head. Therefore when a plate holder reaches a position just outside 30 of the head, one of its lugs 42 engages the arm 192 and opens the contact 195. As soon as the piston is down the contact 244 is closed by the plate 229 carried by the piston and the motors are all supplied with current. While 35 the piston is in other than its lower position the circuit at 244 is of course broken. But at all such times a plate holder which has been ejected from the head has operated the switch 193 to close the contact 195 through its motor 60.

Plate changing mechanism

In commercial work it may frequently become desirable to print a definite number of 40 impressions from a particular plate and to then be able to withdraw such plate from the press and substitute another in its place. We have therefore provided mechanism for automatically accomplishing this purpose without stopping the usual cycle of operation of 45 the press.

Referring to Figures 1—c, 2—b, 7, 8 and 50 9, there are provided four arms 250 shaped as indicated, in order that they may be turned 55 down until their ends touch the track 20 without touching the chain 22, these arms being pivoted at 251. On each side the two arms are joined by connecting rods 252 so that they have a parallel motion. On the 60 face of the bearings of the two furthest from the press, and also pivoting about the pivot 251, are bevel wheels 253. They mesh into a segment of a bevel wheel 254 pivoted at right angles to 251 on the pivot 255 and 65 form part of a casting forming supports for

the solenoid coils 256 and the armature guides 257. These and the shaft 251 are supported by the bracket 258 which is screwed to the side plates 259 which connect the motor base 260 to the frame members 72. There is provided a solenoid on either side of the tracks, the armatures of which move in opposite directions. The armature is so shaped at its end that when the current passes through the coils 256 they are forced out over the track 70 20 against the force of a spring 261 and are turned out of the way about the pivot 255 by the front rollers 29 when a plate reaches that point. This movement is transferred to the arms 250 through the bevel gears 253 and 254 75 and the rods 252. The ends of the arm 250 carry sockets 262 in which rest the rollers 29 of a plate holder to be put on the press. The arms 250 are normally in the shown position by counter weights 263 and are prevented 80 from leaning further away from the press by stops 264, projecting laterally from the side plates 259. Cutaway sections of the tracks 20 are normally filled so as to form smooth track surfaces, by the arc segments 265 which are 85 attached to the arms 266 pivoted at the pivots 267. Spring catches 268 permanently attached to the arms 250, hook over the ends of the arms 269. A standard counter 270 capable of closing an electric current when a predetermined count has been made is connected to and forms part of the switch elements 53 already described, the unit's counter element 90 being connected to the switch element 53 adjacent thereto. When a predetermined number 95 has been recorded, a circuit is closed by the counter in known manner, which circuit includes the solenoids whose armatures are forced out over the tracks. The front rollers 29 of the next plate that comes along push 100 the ends of the armatures around out of the way which turns the rods 250 about their pivots 251. As soon as they have passed the center line, the weight of the plate and plate holder continues the motion until the plate 105 holder rollers are deposited on the tracks 20 when the rods 250 are returned to normal position by the counterweights 263 acting directly on the two right axes 251 and the connecting arms 252. In the meantime the arc 110 segments have been revolved away from the cutaway sections of the tracks by the catches 268. These catches slide over the ends of arms 269 before the arc segments 265 come in contact with the chains 22. The rollers 29 of the old plate that is to be removed follow directly behind the segments 265 and drop through the exposed cutaway sections of the tracks and travel down the inclines 271 and 272. These are so arranged as to angle that 115 one of the lugs 42 on the plate holder turns the switch arm 44 and counter just as it disengages itself in its down motion from the driving link 34 or 35 as the case may be. The plate holder then travels down to a conven- 120 125 130

ient point to be removed by hand when convenient.

The lower part of 272 is hinged so that the rear rollers 29 can pass under this portion to thereby permit the plate holder to be withdrawn.

The action of the lugs 42 on the arm 44 of the switch causes the switch elements 53 to be reversed and the leading lugs of the chain 10 snapped by the lugs 42 on the new plate holder while the following lugs engage the lugs 42 on the new plate holder which then begins its travel towards the printing head.

To explain the operation of the counter it 15 will be understood that since there is a plate holder withdrawn from an upper track 21 and a plate holder withdrawn from the track 20, even counts indicated by the counter will represent one plate holder while 20 the odd numbers indicated on the counter will indicate the other plate holder. To therefore have any particular plate holder eject after a predetermined number of printing impressions have been taken from the plate carried 25 thereby, it is only necessary to set the counter for twice the number desired if it is an even 30 plate holder, that is to be removed and in the case of an odd number plate holder the number set on the counter is twice the number of impressions to be made minus one.

The operation of the press has been explained during the description of the parts but in order to clear up any portions of the 35 operation which may have been somewhat difficult to connect together during the detailed description, a general summary of the 40 operation may be helpful.

Assuming four plates are in the printing head and that the piston 5 is in its lowered 45 position, the plate 229 has caused the switch 244 to be closed thereby energizing all of the circuits to the motors 60. The ejection of the plates from the printing head has caused the operation of the switch 193 to thereby 50 actuate contact members 195 and 196. The contact member 195 also closes a circuit through the motor 60 appropriated to a particular pair of chains and therefore when all 55 of the plates have been ejected from the printing head all of the motor circuits are closed through the contact members 195 to the motors. This is to insure the continued operation of the motors because just as soon as the piston 5 begins to rise the contact at 22 60 is broken thereby.

The other contact 196 closes a circuit through the motor 201, which through the cylindrical valve causes low pressure fluid to enter under the piston. When the piston 65 has reached a position where all the plates are in contact with the containers no pressure fluid is admitted to the containers and as soon as the whole system is under low pressure the high pressure is turned on 70 through the instrumentality of the contact

member 236 and the printing is thereby accomplished.

In the meantime the plates which have been ejected from the printing head are conveyed by their respective chains to the end of the 75 tracks 20 where each plate encounters the arm 44 of its reversing switch and its motor being reversed the plate begins to return and during this return passes under the inking roller and under the wiping and polishing mechanisms. The timing is such that printing has been accomplished and the piston has descended so that the printing head is ready to receive the new inked and wiped plates in ample time before their arrival, so that the process is continuous. If, however, there should be any tardiness in the piston's descent the motor circuits are broken by the plates just before they enter the printing head by contact with the switch arm 192. 80

If it is desired to remove any particular plate and substitute another the counter 270 is set at the proper number and the particular plate is thrown out automatically and a new plate substituted.

What is claimed as new is:

1. In an intaglio printing press, the combination with a fluid pressure container having a flexible wall through which the fluid pressure is applied to a printing plate, 95 of means for automatically positioning a plate for printing and removing it after printing.

2. In an intaglio printing press, the combination with a fluid pressure container having a flexible wall through which the fluid pressure is applied to a printing plate, 100 of means for automatically positioning a plate for printing and removing it after printing and re-positioning it for printing, 105 and automatic means for inking and wiping said plate between successive positioning operations.

3. In an intaglio printing press, the combination with a fluid pressure container 110 having a flexible wall through which the fluid pressure is applied to a printing plate, of means for automatically positioning a plate for printing and means operating in timed relation therewith for introducing 115 fluid pressure into said container.

4. In a printing press the combination with a printing head; of a plurality of pressure containers independently movable in said head and means for automatically introducing plates to be printed adjacent a plurality of said containers.

5. In a printing press the combination with a printing head; of a plurality of rigid pressure containers independently movable in said head, each container having a flexible wall through which fluid pressure is applied to a printing plate.

6. In an intaglio printing press, the combination with a pressure head and a bed rela- 120 125 130

- tively movable, of a plurality of rigid fluid pressure containers each having a flexible wall through which the fluid pressure may be applied for printing, said containers arranged one above another between the head and bed, and independently movable.
7. In an intaglio printing press, the combination with a pressure head and a movable bed, of a plurality of fluid pressure containers each having a flexible wall through which the fluid pressure may be applied for printing and a rigid surface for supporting a plate to be printed, the said surface of each container being adjacent the flexible wall of the next container.
8. In an intaglio printing press, the combination with a head and a movable bed, of a plurality of fluid pressure containers situated between the head and bed, each having a flexible wall through which fluid pressure may be applied for printing and, a rigid surface for supporting a plate to be printed, said containers being normally separated sufficiently to permit the positioning of a plate against the rigid surface of one container and adjacent the flexible wall of the next container, means for moving said bed to bring the containers and plates into close contact and for applying fluid pressure to said containers sufficient to cause printing.
9. In an intaglio printing press, the combination with a printing head, of a plurality of plates adapted to be introduced into said head, means on opposite sides of the head for inking and wiping the plates to be printed, means for introducing an inked and wiped plate into said head from one side thereof, said means acting to eject a plate that has been printed, and means for conveying said ejected plate to the inkers and wipers on the other side of said head.
10. In an intaglio printing press, the combination with a printing head, of a plurality of plate holders adapted to be introduced into said head, a conveyor on opposite sides of said head, means for operating said conveyors in opposite directions simultaneously, with provisions whereby a plate holder on one conveyor at one side of the head ejects a plate holder in the head to the conveyor on the opposite side thereof.
11. In an intaglio printing press in combination a printing head and a movable bed, means for delivering a plate to said head, means for applying fluid pressure to the bed, means for applying fluid pressure on the plate to cause printing, and means controlled by the plate-delivering means to determine when the pressure-applying means shall be brought into operation.
12. In an intaglio printing press in combination a printing head, means operating in cyclic sequence to deliver a plate to be printed to said head, operate said head to print from said plate and remove the printed plate from the head, and means for substituting a new plate for a used plate without stopping said cyclic sequence of operation.
13. In an intaglio printing press the combination with a pressure head and a movable bed, of a plurality of pressure units each having a flexible wall through which pressure may be applied for printing, and a rigid surface for supporting a plate to be printed, the said surface of each unit being adjacent the flexible wall of the next unit.
14. In a printing press the combination with a printing head; of a rigid fluid pressure container movable therein and having a flexible wall adjacent a printing surface of a plate to be printed and means for automatically positioning the plate adjacent the flexible wall of said container and removing it after printing.
15. In an intaglio printing press the combination with a pressure head and a movable bed, of a group of fluid pressure containers each having a flexible wall through which the fluid pressure may be applied for printing, and a rigid surface for supporting a plate to be printed, the said surface of each container in said group being adjacent the flexible wall of the next container.
16. In a printing press the combination with a printing head; of means for alternately introducing a plate into said head and removing it therefrom, the introduction of one plate acting to eject a second plate previously positioned, the second plate acting in turn to eject the first plate.
17. In a printing press the combination with a printing head; of means for alternately introducing a plate into said head and removing it therefrom, the introduction of one plate acting to eject a second plate previously positioned, the second plate acting in turn to eject the first plate, and means for automatically inking and wiping a plate between successive positioning operations.
18. In a printing press, the combination with a pressure container and flexible medium therein, capable of distributing pressure approximately uniformly over an irregular plate surface, of means for automatically positioning a plate for printing and means operating in timed relation therewith for applying pressure through the flexible material to the plate surface.
19. In a printing press, the combination with a pressure container and flexible medium therein, capable of distributing pressure approximately uniformly over an irregular plate surface, of means for automatically positioning a plurality of plates in succession for printing and means operating in timed relation therewith for applying pressure through the flexible medium to each plate surface in succession.
20. In a printing press, a plurality of pressure containers each having a flexible ma-

- material therein capable of distributing pressure approximately uniformly over irregular plate surfaces and means for approximately simultaneously positioning plates to be printed between said containers.
21. In a printing press, a plurality of pressure containers each having a flexible material therein capable of distributing pressure approximately uniformly over irregular plate surfaces, and means for approximately simultaneously positioning plates to be printed between said containers and means operated in timed relation thereto for applying pressure to all said plates through the said flexible mediums simultaneously.
22. In a printing press, the combination with a pressure head and a bed relatively movable, of a plurality of pressure containers each having a flexible material therein capable of distributing pressure approximately uniformly over irregular plate surfaces, said containers so arranged that plates to be printed can be placed between them approximately simultaneously and means for bringing pressure on all the plates simultaneously through the flexible mediums, said containers arranged one above the other between the head and bed.
23. In a printing press, the combination with a pressure head and movable bed, of a plurality of pressure containers each having a flexible material therein capable of distributing pressure approximately uniformly over irregular plate surfaces, and a rigid surface on each container adjacent to the flexible material of the next container for supporting a plate to be printed.
24. In a printing press, the combination with a head and movable bed; of a plurality of pressure containers situated between the head and the bed, each container having flexible material therein through which pressure may be applied for printing and a surface for supporting a plate to be printed, said containers being normally separated sufficiently to permit the positioning of a plate against such surface of one container and adjacent to the flexible material of the next container, and means for moving said bed to bring the containers with the flexible materials and plates in close contact and for applying pressure to the plates through the flexible materials sufficient to cause printing.
25. In a printing press, the combination of a pressure container and a flexible material therein capable of distributing pressure approximately uniformly over an irregular plate surface; of means for introducing a plate to be printed by said container from one side, the introduction of a plate from the other side acting to eject the previously positioned plate on the side from which it was positioned.
26. In an intaglio printing press, the combination with a printing head; of a plurality of plates adapted to be introduced into said head, means on opposite sides of said head for inking and wiping the plates to be printed, means for introducing an inked and wiped plate into said head from one side thereof, said means acting to eject a plate that has been printed, and means for conveying said ejected plate to the inkers and wipers on the other side of said head.
27. In a printing press, the combination with a pressure container and a flexible material therein capable of distributing pressure approximately uniformly over an irregular plate surface; of a plurality of plates adapted to be positioned in contact with the flexible material in succession for printing, and means for inking and wiping such plates in succession by the same inker and wiper and delivering the inked and wiped plates successively to said position.
28. In an intaglio printing press, the combination with a printing head; of a plurality of plate holders adapted to be introduced into said head, a conveyor on opposite sides of said head, means for operating said conveyors in opposite directions simultaneously, with provisions whereby a plate holder on one conveyor at one side of the head ejects a plate holder in the head to the conveyor on the opposite side thereof.
29. In an intaglio printing press, in combination, a printing head and movable bed, means for delivering a plate to said head, means for moving the bed so as to bring the plate in contact with the printing pressure material, means for applying pressure on the plate to cause printing and means controlled by the plate delivering means to determine when the pressure applying means shall be brought into operation.
30. In an intaglio printing press, in combination, a printing head, means operating in cyclic sequence to deliver a plate to be printed to said head, operate said head to print from said plate and remove the printed plate from the head, and means for substituting a new plate for a used plate without stopping said cyclic sequence of operation.
31. In an intaglio printing press, the combination with a pressure head and movable bed, of a plurality of pressure units each having a flexible wall through which pressure may be applied for printing and a rigid surface of each unit being adjacent to the flexible wall of the next unit.
